CLAIM

The ornamental design for a data cable lanyard, as shown and described.

DESCRIPTION

FIG. 1 is a top, front and right side perspective view of a data cable lanyard showing our new design;

FIG. 2 is a top, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and right side perspective view showing the data cable lanyard in a first alternate position;

FIG. 10 is a top, front and left side perspective view showing the data cable lanyard in a second alternate position; and,

FIG. 11 is an enlarged view of portion 11 in FIG. 1.

The broken lines in the drawings illustrate portions of the data cable lanyard which form no part of the claimed design. The data cable lanyard is shown with a symbolic break in its length. The appearance of any portion of the article between the break lines forms no part of the claimed design.
